UNITED STATES PATENT OFFICE.

LOUIS HAVASY, OF LOS ANGELES, CALIFORNIA.

ARTIFICIAL-FIBER-WOOD CONSTRUCTION.

1,407,747.

Specification of Letters Patent. Patented Feb. 28, 1922.

Application filed June 24, 1920. Serial No. 391,541.

To all whom it may concern:

Be it known that I, LOUIS HAVASY, a citizen of the United States, residing at Los Angeles, in the county of Los Angeles and State of California, have invented and discovered a new and useful Artificial-Fiber-Wood Construction, of which the following is a specification.

An object of this invention is to provide an artificial fiber wood construction that is adaptable to a wide range of use in the industrial and ornamental arts, and which can be employed in each distinct and separate manufacture without change in its composite parts.

Pulps as heretofore employed, have been compounded usually for a specific purpose in the manufacture of some distinct article aside from which the pulp has no further use.

An object of this invention is to provide a pulp for general use and it comprises a fibrous composition of the constituency of dough, paste or liquid to be employed in the manufacture of household furniture, artificial limbs, bath tubs, pottery, picture and mirror frames, tile and sheet plates for interior and exterior wall facings and decoration and also various moldable articles, and the final structure completed as hereinafter set forth.

An object of this invention is to provide an artificial fiber wood structure that will be strong, and durable, and cheap of manufacture; and which will also be fire and water proof.

Another object is to provide a pulp especially adapted to exterior ornamentation by such methods as hand modeling for sculpture effects.

Another object is to provide a pulp that in plastic state will readily mix and retain color so that in making various objects or decorations, artistic effects can be obtained.

In this invention I provide a pulp that can be glazed after it is molded into a desired form, thus to give the molded object a smooth exterior surface.

Other objects, advantages and features of invention may appear from the accompanying drawings, the subjoined detail description and the appended claims.

The discovery and invention may be understood by the following description, reference being had to the accompanying drawings which illustrate various objects

and articles formed with my artificial fiber wood.

Figure 1 is a front perspective view of my novel structure as applied in an ornamental drawing room desk, a major part of which is formed with my fiber wood.

Fig. 2 is a section on line x^2 , Fig. 1.

Fig. 3 is a perspective view of the skeleton frame employed in construction of desk shown in Fig. 1.

Fig. 4 is an elevation of an artificial arm formed of my fiber wood structure, parts being in section to show the arm socket at the shoulder, and the joint connection at the wrist and elbow.

Fig. 5 is an enlargement of the hand shown in Fig. 4 with wrist and lower forearm in section to show detailed construction and joining of parts.

Fig. 6 is a side elevation of an artificial foot and lower limb, formed with my fiber wood construction, partly in section; different positions of foot being shown by dotted lines.

Fig. 7 is a section on line x^7 , Fig. 6.

Fig. 8 is a front elevation of an artistic mirror frame formed of my artificial fiber wood structure.

Fig. 9 is a section on line x^9 , Fig. 8.

Fig. 10 is a front view of a tile or decorative plate formed of my artificial fiber wood structure.

Fig. 11 is a section on line x^{11} , Fig. 10.

Fig. 12 is an axial section through a bath tub formed of my artificial fiber wood structure.

Fig. 13 is an axial section through a leg for furniture construction composed principally of my artificial wood and showing a reinforced center staff therein and a caster attached to the staff.

In preparing the composition I prefer to use the ingredients in about the following proportions, the parts being given by weight as follows: viz: fifty-six pounds of fiber pulp, thirty-four pounds of magnesite and ten pounds of asbestos mixed with liquid magnesia chloride 22° Baumé to a consistency adapted to fulfill requirement to pour or to make a paste or dough to be molded.

Good results may be obtained, however, when the ingredients are varied within the following limits: fifty to sixty pounds of fiber pulp, thirty to forty pounds of magnesite and five to fifteen pounds of asbestos mixed with magnesia chloride 17° to 27°.

Baumé to requirement to pour, or to form a paste or dough to be molded.

I obtain my fiber pulp from any fibrous material, such as waste wood or lumber, saw dust, paper, straw, leaves, cane or corn stalks, properly disintegrated. This fiber I combine with the other ingredients as before stated and mix to requirements.

When my artificial fiber wood is to be used

- 10 in the construction of furniture or other things requiring a metal or wood frame support as shown in Figs. 1, 2, 3, 13, I make the wooden supports fire proof by painting them with a non-combustible paint before
- 15 moulding, pasting or pouring my artificial fiber wood around the frames.

I prepare this fire proof paint by mixing the composing ingredients in about the following proportions, viz: forty parts lime, twelve and one-half parts cooking salt, fifteen parts alum, and thirty-two and one-half parts wolframate of sodium or sodium tungstate.

This fire proof paint I apply to the wood reinforcement or frame of furniture and after it dries I apply my artificial fiber wood by pouring into prepared form or dies, pasting it on, or by hand modeling the doughy mass into a desired form.

30 In constructing furniture, as for instance, the desk 1 shown in Figs. 1, 2, 3, various molds, not shown, are used to enclose the frame 2, after which the pulp is applied to fill the molds and form the desk with drawer enclosures 3.

Drawers 4 are provided that have wood reinforcements 5 that are made fire proof by application of my paint as applied to frame 2.

40 Legs 6 of frame 2 if desired can be provided with roller casters 7 so as to support the desk 1 clear of the floor.

When my artificial fiber wood is used in the construction of artificial limbs it is preferably mixed to a dough that can be modeled into a desired size and form to suit the individual for whom it is constructed; and a flesh color added to the dough corresponding to the natural color of the proposed wearer.

50 When a full arm 8 is formed as shown in Fig. 4, the upper arm is provided at the shoulder with a socket 9 that can be formed to fit the stub end of the wearer's arm. At the elbow and wrist, arm 8 is provided with ball and socket joints 10, 11 that permit a limited natural movement or swing of the joined parts.

In constructing joints 10, 11, the ball portions 10, are formed first and after they have hardened they are polished to give them a smooth finish. Then the balls are immersed in melted paraffin which when cooled forms a thin coat 12 over the balls. Then the socket ends 11 of the arm are formed over the balls; and, after the socket ends have

hardened the paraffin is subjected to heat and permitted to escape from the joints, after which lubricating oil is injected to facilitate a free movement of parts. By this construction inseparable joints are formed which connection of parts can be made by the artist modeler to assume the graceful swing or movement of a natural arm.

A different form of joint is shown in Figs. 6, 7 in which a steel ball 13 and socket 14 are interposed between the foot and leg 15, 16.

A clearance is left between the foot and lower limb so that there is a limited movement of the foot on ball 14. The lower end 80 of the limb 16 has inclined sides 17 that correspond to similar inclined sides 18 on the foot 15 and these slides in contacting limit the side movement of the foot relative to the limb; that is the foot has a slight 85 side movement so that it can assume a flat contact when the wearer is travelling over uneven ground.

When my artificial fiber wood is used in molding or modeling picture or mirror 90 frames the pulp can be colored to obtain various artistic effects. As seen in Figs. 8, 9 the frame 19 has four shades 20, 21, 22, 23 which can be of different colors or if desired can be different shades of a single color that 95 is mixed with the dough before the frame is formed.

The frame can be open for a picture, not shown, or it can be provided with a mirror 100 24 that has its edges embedded in the dough; and the back of the mirror and frame can be strengthened by cardboard, or by canvas or board backing 25 cemented thereto.

When my artificial fiber wood is to be used in exterior and interior decoration the tile or 105 plates can be formed in thin sheets 26 which can be placed on a designing table convenient for the artist to engrave or emboss or imprint any desired design thereon, after which the sheets or tile can be secured in place by 110 plastic means. The sheets can have a backing 27 of paper, cheap cloth or wire.

When my artificial fiber wood is used in making toilet appliances such as a bath tub 28, it is molded into the desired shape and then the entire surface is subjected to polishing. If desired, the inlet water pipe 29, outlet pipe 30 and over-flow pipe 31 can be 115 molded into the wall of the tub leaving the necessary pipe ends extending for pipe and 120 fixture connections.

My artificial fiber wood is especially adapted to the construction of furniture fixtures requiring great artistic skill in modeling and embossing thereon desired decorative effects, as it can be reduced to the right pliability to be molded into any desired form and retain that shape without cracking, sagging or excessive shrinking.

As seen in Fig. 13 the furniture leg 32 is 130

formed around a straight upright wood support 33 that is made fire proof as previously stated. The leg 32 has an elongated forward extension 34 unsupported by anything but 5 the tenacity of the fibrous composition, also the back portion of the leg 32 has the enlargements 35, 36 that are formed without sagging, owing to the disposition of the composition to retain its shape when uneffected 10 by modeling force.

In operation my artificial fiber wood is prepared as previously stated to pour, plaster or mold, after which it is used by the artist or modeler to express his artistic ideas.

15 I claim.

1. In the construction of furniture, the combination with a composition containing fifty-six parts vegetable fiber, thirty-four parts magnesite, ten parts asbestos mixed 20 with magnesia chloride 22° Baumé, to requirements for pouring, pasting or molding, and a wooden frame coated with a composi-

tion containing forty parts lime, twelve and one-half parts cooking salt, fifteen parts alum, and thirty-two and one-half parts 25 wolframate of sodium.

2. In the construction of furniture having drawers therein, the combination with a composition containing fifty-six parts vegetable fiber, thirty-four parts magnesite, ten parts 30 asbestos mixed with magnesia chloride 22° Baumé, to requirements for pouring, pasting or molding; and wooden frames for the body portion and drawers of said furniture; said wooden frames being coated with a composition containing forty parts lime, twelve and one-half parts cooking salt, fifteen parts alum and thirty-two and one-half parts 35 wolframate of sodium.

In testimony whereof, I have hereunto set 40 my hand at Los Angeles, California, this 16 day of June, 1920.

LOUIS HAVASY.
